UNITED STATES PATENT OFFICE.

CARROL R. BOYCE, OF WAUTOMA, WISCONSIN.

AUTOMATIC TOOL-DROPPING MACHINE.

1,422,531.

Specification of Letters Patent. Patented July 11, 1922.

Application filed May 18, 1921. Serial No. 470,724.

To all whom it may concern:

Be it known that I, CARROL R. BOYCE, a citizen of the United States of America, residing at Wautoma, in the county of 5 Waushara and State of Wisconsin, have invented certain new and useful Improvements in Automatic Tool-Dropping Machines, of which the following is a specification.

10 The primary object of the present invention is the provision of a strong machine adapted for dropping tools such as pounding weights or boring tools after elevating the same a proper distance, a great saving in 15 power being provided by my machine and the dropping operation being automatic during the continuous operation of the source of power.

20 A further object of the invention is the provision of a machine after the nature of a pile driver adapted for elevating the weight with only a slight expenditure of power and automatically releasing the weight when reaching its highest elevated 25 point for the dropping operation.

25 A still further object of the invention is the provision of a hoisting gear for tools to be dropped so arranged that the gear is automatically unclutched from power mechanism when the tool reaches its highest elevated position, means being also provided to temporarily increase the speed of the gear immediately preceding such releasing operation.

35 With these general objects in view the invention consists of the novel combination and arrangement of parts hereinafter more fully described in connection with the accompanying drawings and in which like reference characters designate corresponding parts throughout the several views.

In the drawings,

Figure 1 is a side elevation of the machine with the weight elevated.

40 Figure 2 is a similar view thereof with the weight in its lowered position.

Figure 3 is a top plan view of Figure 1,

45 Figure 4 is a horizontal transverse sectional view taken longitudinally of the power shaft shown in Figure 3, with parts removed and broken away, a protecting casting for the spring of the clutch being also shown in section,

50 Figures 5, 6 and 7 are vertical transverse

sectional views taken upon lines V—V, 55 VI—VI and VII—VII respectively, of Figure 4, and

Figure 8 is an end view of the elevating beam showing the pitman connection therefor.

Referring more in detail to the drawings, my invention being in the nature of a tool-dropper may be arranged for elevating and automatically dropping any desired number of weights or tools and one form of the invention is herein fully set forth embodying all of the principles thereof in a single unit or machine for elevating and dropping a single member such as the weight 10. A suitable base or frame 11 is provided for 70 the machine herein illustrated rectangular in form, for resting upon the ground and constituting a support for the operating mechanism as well as the corner post 12, having a pulley 13 adjacent its upper end 75 and over which the hoisting cable 14 of the weight 10 passes.

A driving shaft 15 is journaled transversely of the frame 11 adjacent the opposite end thereof from the post 12 and has 80 a power pulley 16 for turning by any suitable source of supply, which is unnecessary to herein illustrate.

A power shaft 17 is journaled transversely of the frame 11 forwardly of the driving 85 shaft 15, and is provided with a gear 18 freely mounted upon the power shaft 17, by a hub 19, while the gear 18 is in constant mesh with a pinion 20 secured to the driving shaft 15.

An elevating beam 21 for the cable 14 is pivoted at its lower end upon a stub shaft 22 projecting from the enlarged lower end or base 23 of the post 12. The cable 14 after passing from the weight 10 over the 95 elevated pulley 13 passes over the sheave 24 journaled upon a shaft 25 adjustably carried by the bifurcated free end portion 26 of the beam 21, a plurality of perforations 27 being provided for the adjustable positioning of said shaft 25. The lower end portions 28 of the beam 21 is bifurcated for the reception of a third pulley 29 journaled upon stub shaft 22 and over which the cable 14 passes from the intermediate pulley 24, 100 the adjacent end of the cable 14 being anchored upon a spindle 30 projecting from the base 23 and having a squared end 31

adapted for the detachable connection of a crank handle such as illustrated by dotted lines at 32 in Figure 1 of the drawings.

A crank 33 fixed to one end of the power shaft 17 is pivotally connected to the beam 21 by a pitman 34 having one end thereof pivoted as at 35 to the crank 33 and its other end provided with a fork 36 pivoted upon the shaft 25. The hub 19 has a toothed clutch portion or inner end 37 adapted to cooperate with a slidable clutch sleeve 38 mounted upon the shaft 17 and having opposite slots 39 adapted for the slidable reception of projections 40 carried by a sleeve 41 fixed to the shaft 17. A spring 42 surrounds the sleeve 41 and the adjacent portion of the clutch member 38, the said spring being tensioned between an annular shoulder 43 substantially centrally of the clutch member 38 and a similar shoulder 44 upon the sleeve 41. The spring 42 normally maintains the clutch members 37 and 38 in operative engagement, the clutch being adapted for manual release by a suitable clutch lever 45 bearing against the opposite side of the shoulder 43 from the spring 42.

A tubular casing 46 is preferably provided around the spring 42 for overlying the slots and projections 39 and 40 and preferably secured to the shoulder 43. A sleeve 47 is secured to the shaft 17 and is mounted within a socket 48 of the hub 19 and a similar socket 49 of the clutch member 38 for preventing movement of the hub 19 longitudinally of the power shaft 17. A transverse pin 50 carried by the shaft 17 is positioned in the opposite longitudinal interior grooves 51 of the clutch member 38 which project inwardly of the clutch member 38 from the socket 49 thereof. The pin 50 prevents rotation of the clutch member 38 relatively of the power shaft 17, and taken with the dove-tailed connection of said clutch member 38 with the sleeve 41, the turning of the gear 18 in the direction indicated by the arrow in Fig. 2 of the drawing, effects the rotation of the power shaft 17 with its crank 33 when the clutch members 37 and 38 are in engagement with each other as normally maintained by the spring 42.

With the weight 10 in its lowered position as illustrated in Fig. 2, the turning of the gear 18 by the pinion 20 pulls the pitman 34 thereby swinging the beam to its lowermost position and elevating the weight 10 as illustrated in Fig. 1. After the crank 33 passes the longitudinal line of center of the pitman 34, the weight 10 exerts a forward pull upon the pitman and crank, thereby turning the crank 33 and the clutch member 38 at a greater rate of speed than the gear 18 and clutch member 37, permitting the clutch member 38 to ratchet over the clutch member 37 while the weight 10 drops and

the beam 21 returns to the position shown in Fig. 2. It will be seen that the continued rotation of the gear 18 at a uniform speed successively elevates the weight 10 which is automatically released by the clutch members 37 and 38 for dropping for use in driving pipe, piling or other objects. It will be obvious that a drilling tool may be employed instead of the weight 10 while the operative position of the tool or weight is regulated by turning the shaft 30.

Not only is the length of the cable 14 adjusted as desired, by means of the shaft 30 for the regular operation of the machine but the shaft 30 may also be employed for elevating the tool or weight attached to the cable from any lowered position such as a well or pit, and for elevating the weight for positioning a new pipe during pipe driving. Only little power is required to operate the machine by means of the pinion 20 while the weight or tool is permitted to drop the entire distance raised, little wear being given the cable 14 as the cable only travels over the single pulley 13 during the usual operation of the device. The operative power can be instantly released by the hand clutch lever 45 whenever desired, and the crank 32 employed for winding up the cable 14.

An accelerating attachment is mounted upon the crank 33 consisting of an arm 52 having a weight 53 at one end and pivoted to the crank 33 at its opposite end 54. A strap 55 limits the swinging movement of the arm 52 and just preceding the instant that both the crank 33 and pitman 34 reach like positions as shown in Figure 1, the weight 53 swings the arm 52 against the inner end of the crank 33, as shown in Figure 1, giving a sudden forward impulse to the crank 33 causing a quicker release of the clutch 37 and 38 and more quickly bringing the weight 10 to its dropping position for automatic release and operation. The complete operation of the device will be apparent from this detailed description thereof and while the form herein set forth is believed preferable, it will be understood that changes may be made therein without departing from the spirit and scope of my invention.

What I claim as new and desire to secure by Letters Patent, is:—

1. A tool-elevating machine comprising an inclined beam mounted for oscillations, a cable adjustably attached to the beam, a tool secured to the free end of the cable, a power shaft, a crank upon said shaft, pitman connections between said shaft and beam, a propelling gear upon said shaft, clutch members between said shaft and gear adapted for automatic release when the tool is at its most elevated position, manual releasing means for a clutch, adjustable winding means for the cable and an accelerating means for the

crank carried by the crank adjacent the power shaft.

2. A device of the class described comprising a base, a beam pivoted at its lower end to the base with a bifurcated free end portion provided with transverse perforations, a shaft adjustably positioned through one pair of said perforations, a sheave journaled upon said shaft between the bifurcations of the beam, a pulley journaled at the pivoted end of the beam, a post carried by the base, a pulley adjacent the top of the post, an elevating cable running over said pulleys with an intermediate portion positioned over said sheave, a spindle to which the cable is anchored adapted for rotation during the winding of the cable thereon, a tool upon the free end of the cable, a power shaft carried by the base, a clutch member adjustably attached to said shaft, a crank secured to the shaft, a pitman pivotally connected between the free end of said crank and said shaft upon the beam, a propelling gear journalled upon said power shaft normally operatively connected to said clutch member and adapted for automatic release when the tool is elevated, an accelerating means upon the crank adjacent the power shaft comprising an arm pivoted to the crank, a weight at the free end of the arm extending beyond the end of the crank and a limiting strap for the arm carried by the crank.

15 10 15 20 25 30 35 40

3. A device of the class described comprising a base, a beam pivoted at its lower end to the base with a bifurcated free end portion provided with transverse perforations, a shaft adjustably positioned through one pair of said perforations, a sheave journaled upon said shaft between the bifurcations of the beam, a pulley journaled at the pivoted end of the beam, a post carried by the base, a pulley adjacent the top of the post, an elevating cable running over said pulleys with an intermediate portion positioned over said sheave, a spindle to which the cable is anchored adapted for rotation during the winding of the cable thereon, a tool upon the free end of the cable, a power shaft carried by the base, a clutch

member adjustably attached to said shaft, a crank secured to the shaft, a pitman pivotally connected between the free end of said crank and said shaft upon the beam, a propelling gear journalled upon said power shaft normally operatively connected to said clutch member and adapted for automatic release when the tool is elevated, an accelerating means upon the crank adjacent the power shaft comprising an arm pivoted to the crank, a weight at the free end of the arm extending beyond the end of the crank and a limiting strap for the arm carried by the crank.

4. In a device of the class described, a power shaft, a gear having a hub journaled thereon and provided with clutch teeth at one end of the hub with a recess in the hub surrounding the shaft adjacent said teeth, a sleeve within said recess fixed to the shaft adapted for preventing longitudinal movement of the gear, a clutch member longitudinally slidable upon the shaft having teeth adapted to cooperate with the adjacent end of the hub and having an inwardly projecting recess adapted for overlying said sleeve when the clutch is in its engaging position, the said clutch member having inwardly extending opposite grooves, adjacent the shaft, a transverse pin through the shaft projecting into said grooves, a sleeve secured to the opposite end portion of the shaft from said gear having projections extending toward the gear, said clutch member having slots in which said projections are normally positioned whereby longitudinal movement of the clutch member is permitted but rotation relatively of the power shaft is prevented and a spring tensioned between said last named sleeve and clutch member whereby the clutch is normally closed during operation.

In testimony whereof I affix my signature.
CARROL R. BOYCE.
